UNITED STATES PATENT OFFICE

2,349,121

REFRIGERATOR

Christian Steenstrup, Schenectady, N. Y., assignor to General Electric Company, a corporation of New York

Application March 30, 1940, Serial No. 326,919

8 Claims. (CL 62—99)

My invention relates to refrigerators, and particularly to refrigerators of the type in which a compartment is cooled by a cooling element arranged in the upper portion thereof in order to produce a natural circulation of air.

It is a common practice to construct household refrigerating machines with food storage compartments cooled by evaporators arranged in the upper portion of the compartments so that the natural tendency of cold air to circulate downward may be employed to maintain a circulation of air throughout the compartment to be cooled. The arrangement of the cooling unit in the top of the compartment tends to cool the upper portion of the inner cabinet walls or liner near the evaporator and to maintain that portion at a lower temperature than other portions thereof. This is particularly true in mechanical refrigerators provided with motor-compressor units arranged directly below the compartment to be cooled, since a portion of the heat from the refrigerating machine passes upwardly through the insulation in the bottom wall of the cabinet. It sometimes becomes desirable to prevent uneven distribution of temperatures throughout the cabinet liner, and particularly to prevent the passage of heat through the bottom of the cabinet directly to articles placed in the lower portion of the food compartment formed by the cabinet liner. For example, it is a frequent practice to support containers adapted to hold vegetables and similar foods in the lower portion of the food compartment. These containers are adapted to prevent any substantial dehydration of the articles contained therein. When such containers are so placed, it may happen that the reduced circulation of air is sufficient to allow a substantial rise in temperature of the bottom wall of the compartment such that the articles in the closed container are not maintained at a sufficiently low temperature. Accordingly, it is an object of my invention to provide a refrigerator including a food compartment and an improved arrangement for insuring adequate cooling of the lower portion of the compartment.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawings in which Fig. 1 is a perspective view of a household refrigerator embodying my invention; Fig. 2 is a sectional side elevation view, of a portion of the refrigerator shown in Fig. 1; Fig. 3 is a sectional side elevation view of a modification of the invention shown in Fig. 1; and Fig. 4

is a front elevation view of the modification shown in Fig. 3.

Referring now to the drawings, in Fig. 1 I have shown a refrigerator having a thermally insulated cabinet 10 and a food storage compartment 11 to which access may be gained by opening a door 12. The compartment 11 is arranged to be cooled mainly by a cooling element 13 disposed in one portion or region of the compartment, preferably in the upper portion thereof, and constituting the evaporator or heat absorbing portion of a primary refrigeration system. A supplementary cooling system of the secondary type is provided and includes a cooling portion 14 constructed and arranged for cooling another portion or region of the compartment, as the lower portion thereof, and a condenser portion 15 in the vicinity of the evaporator 13, the portions being joined by conduits 16. In order to vary the effect, or heat exchange, of the evaporator 13 on the condensing portion of the secondary system, I have provided means for varying the distance between the evaporator and the condensing portion, as hereinafter described.

The evaporator 13 is connected in the refrigerant circuit of a refrigerating machine including a motor-compressor unit arranged in a machinery compartment within the cabinet 10 below the compartment 11. Access to the machinery compartment may be had by removing a panel 10a. The motor-compressor unit has been omitted from the drawings for purposes of clarity. Refrigerant is supplied to the evaporator 13 through a liquid line 17 and float chamber 11a and vaporized refrigerant is returned to the motor-compressor unit through suction line 18.

During the operation of the refrigerating machine, the air at the top of the compartment 11 is cooled by the evaporator 13 and circulated downwardly, the warmer air in the lower portion of the cabinet rising to take its place, the circulating air absorbing heat from the articles within the cabinet.

As shown in Fig. 2, the cabinet 10 includes an outer metal casing 19 and a liner 20 of metal or other suitable material forming the sides and top and bottom walls of the food compartment 11. The space between the casing 19 and liner 20 is filled with heat insulating material 21 to minimize the transfer of heat to the food compartment. Since the evaporator 13 is arranged in close proximity to an upper side wall of the liner 20, it tends to maintain that portion at a lower temperature than the bottom wall. In a household refrigerator, it is frequently desirable to place closed containers adjacent the bottom of the food compartment for maintaining high relative humidity therein to prevent dehydration of certain foods such as vegetables. In Fig. 1, I have shown a partition 22 supported by a frame 23, the frame

being provided with depending flanges having inturned portions for supporting a food storage receptacle, not shown. The frame 23 is preferably spaced from the liner 20 as by supporting brackets 23a. With such an arrangement it is obvious that there will be a limited circulation of air around the receptacle or container and there is, therefore, less cooling capacity available to absorb heat entering the food compartment through the bottom wall thereof. It is, therefore, desirable to provide some arrangement for lowering the temperature of the lower portion of the liner 20. I have found that the additional cooling required may be obtained effectively by providing a container partially filled with a liquid vaporizable at the temperatures prevailing at the bottom of the food compartment and including a liquid vaporizing portion secured in good heat exchange relation with the bottom of the liner and a second portion for condensing the vapor arranged in good heat exchange with the evaporator.

In the embodiment illustrated I provide a closed conduit 16, the cross-section of which is flat on one side so that it may be secured in good heat exchange relation with the liner 20, as shown in Fig. 2. The conduit is provided with a plurality of turns 14 forming a cooling portion secured to the bottom side and back walls of the liner 20 and a plurality of turns 15 forming a condensing portion adjacent the upper portion of the liner near the evaporator 13. The container or conduit 16 is partially filled with a vaporizable liquid (not shown) so that the turns 14 are maintained flooded therewith. During the operation of the refrigerating machine when the bottom wall of the evaporator is warmer than the upper portion thereof, liquid in the turns 14 will be vaporized and the vapor will rise through the upright portions of the conduit 16 and circulate in the turns 15 where it will be cooled by the heat exchange with the evaporator 13 and will be liquefied, the liquid returning to the lower portion of the conduit. It is, therefore, evident that heat is carried away by the vapor flowing from the bottom portion of the conduit and that the cooled liquid returned thus tends to supplement the cooling of the lower portions of the liner. This arrangement effectively prevents undue heating of articles such as a container disposed adjacent the bottom wall of the food compartment.

The above-described arrangement for providing and equalizing or supplementing the cooling effect in the lower portion of the refrigerator compartment is not part of my invention but is described and claimed in application Serial No. 302,388 of Leonard W. Achison, filed November 1, 1939, and assigned to the same assignee as the present invention.

I have provided means for varying the amount of heat exchange between the condensing portion 15 and the evaporator 13 or the relative effect produced on the condensing portion by the evaporator or cooling element. This is accomplished by varying the distance between the evaporator 13 and the condensing portion 15.

In the form of my invention illustrated in Figs. 1 and 2, I have provided an arrangement for adjustably moving the evaporator 13 with respect to the condensing portion 15 of the secondary system. I have provided a pair of opposed bracket members 24 secured to the top of the liner 20 and serving as tracks upon which the evaporator 13 may slide, the evaporator 13 being provided with outwardly directed flanges 25 for engage-

ment with the brackets 24. As shown in Fig. 2, the liquid and suction lines 17 and 18, respectively, are provided with flexible conduit portions 26 and 27, respectively, as coiled copper tubing, for example. In this form of my invention, the condensing portion 15 is affixed to the liner 20, opposite the rear portion of the evaporator 13 and located in the insulation space between the outer casing 19 and the liner 20. The evaporator 13 is preferably closed at the rear by a metal plate in order to enhance the heat exchange between the evaporator and the condensing portion. In order to cause the evaporator to be moved along the tracks 24 I have provided an adjusting knob 28 having a rod 29 attached thereto, the assembly being supported from the top wall of the liner 20 in any suitable manner as by a substantially U-shaped bracket 30. The end of the rod or stem 29 opposite the knob end is enlarged and threaded, as indicated by the numeral 33 in Fig. 2, the threaded portion being arranged for operative engagement with a suitable threaded opening in an enlarged portion 31a of a suitably arranged cross member 31 supported at either end thereof on the side walls of the evaporator. It will be apparent that to move the evaporator toward the condensing portion 15, the knob 28 will be turned in one direction whereas to increase the distance and thereby minimize the heat exchange between the evaporator and condensing portion the knob will be turned in the opposite direction.

In the form of my invention disclosed in Figs. 3 and 4, the adjustment is obtained by moving manually the condenser portion with respect to the evaporator, the evaporator being secured in any suitable manner to the top wall of the liner 20. As best shown in Fig. 3, the condensing portion 15 is secured to the outer surface of a plate 36 of suitable material, preferably of relatively good heat conducting characteristics, the plate being pivotally supported adjacent the wall of the evaporator, as by means of a pivotal connection 32 to the rear edge of the evaporator itself. The adjusting member, including knob 28, is supported as previously described. The previously described cross member 31 is omitted and in its place the threaded portion 33 threadingly engages a suitable connecting link 34. A second connecting link 35 preferably pivotally attached at each end thereof joins the member or link 34 and the plate 36. Relatively flexible connections 37 and 38, as looped copper tubing for example, join the condensing portion 15 and the conduits 16.

As indicated in Fig. 4, I have provided indicating means 39 on the knob 28 and reference indicia 40 on the front face of the bracket 30 so that the user may be apprised of the relative positions of the evaporator and condensing portion and, accordingly, the degree of the cooling effect established by the cooling portion 14.

The principles of my invention are equally applicable wherever supplementary cooling may be desired. The need for such cooling may be caused in the manner illustrated in Fig. 1 where-in a partition restricts the circulation of air. My invention is equally applicable with one or more pans supported from a suitable frame or shelf or even placed directly on the bottom wall of the cooled compartment. My invention may find application even though circulation is not restricted in order to permit installation of an evaporator 13 of relatively small capacity, the cooling effect thereof being supplemented at a

point or points remote from the evaporator. Moreover, the principles of my invention may be applied wherever it is desired to equalize the temperatures of the liner.

While I have described an embodiment of my invention in connection with a household refrigerator, other applications will readily be apparent to those skilled in the art. For example, I have illustrated a float chamber in the primary liquid refrigerant line. My invention is equally applicable to a system in which refrigerant is supplied to the evaporator through a capillary tube. I do not, therefore, desire my invention to be limited to the particular construction shown and described, and I intend in the accompanying claims to cover all modifications within the spirit and scope of my invention.

What I claim as new and desire to secure by Letters Patent of the United States is:

1. A refrigerator comprising a cabinet having a food storage compartment, a primary refrigerating system including a cooling element located in one region of said compartment, a secondary refrigerating system comprising a cooling portion constructed and arranged for cooling another region of said compartment and a condensing portion located in the vicinity of said cooling element, said condensing portion and said cooling element being arranged for relative movement therebetween for varying the distance between said cooling element and said condensing portion to change the relative effect produced thereon by said cooling element.

2. A refrigerator comprising a cabinet having a food storage compartment, a primary refrigerating system including a cooling element located in one region of said compartment, a secondary refrigerating system comprising a cooling portion constructed and arranged for cooling another region of said compartment and a condensing portion located in the vicinity of said cooling element, said condensing portion and said cooling element being arranged for relative movement therebetween, and manually operable means for varying the distance between said cooling element and said condensing portion to change the relative effect produced on said condensing portion by said cooling element.

3. A refrigerator comprising a cabinet having a food storage compartment, a primary refrigerating system including a cooling element located in one region of said compartment, a secondary refrigerating system comprising a cooling portion constructed and arranged for cooling another region of said compartment and a condensing portion located in the vicinity of said cooling element, said condensing portion and said cooling element being arranged for relative movement therebetween for varying the distance between said cooling element and said condensing portion to change the relative effect produced thereon by said cooling element, and means for indicating the relative positions of said cooling element and said condensing portion.

4. A refrigerator comprising a cabinet having a food storage compartment, a primary refrigerating system including a cooling element located in one region of said compartment, a secondary refrigerating system comprising a cooling portion constructed and arranged for cooling another region of said compartment and a condensing portion located in the vicinity of said cooling element, said condensing portion and

said cooling element being arranged for relative movement therebetween for varying the distance between said evaporator and said condensing portion to change the relative effect produced thereon by said cooling element, and manually operable means for adjustably moving said condensing portion with respect to said cooling element for changing the relative effect produced thereon by said cooling element.

5. A refrigerator comprising a cabinet having a food storage compartment, a primary refrigerating system including a cooling element located in one region of said compartment, a secondary refrigerating system comprising a cooling portion constructed and arranged for cooling another region of said compartment and a condensing portion located in the vicinity of said cooling element, said condensing portion and said cooling element being arranged for relative movement therebetween for varying the distance between said evaporator and said condensing portion to change the relative effect produced thereon by said cooling element, and means for adjustably moving said cooling element with respect to said condensing portion to change the relative effect produced on said condensing portion by said evaporator.

6. A refrigerator comprising a cabinet having a food storage compartment, said compartment being provided with a metal liner, a primary refrigerating system including a cooling element located in said compartment, said cooling element having a plurality of walls defining a region of relatively low temperature, a secondary refrigerating system comprising a cooling portion in thermal contact with a portion of said lining and a condensing portion in the vicinity of said cooling element, a plate of heat conductive material pivotally supported adjacent a wall of said cooling element, said condensing portion being supported by said plate, and means for adjustably moving said plate and said condensing portion with respect to said cooling element for changing the relative effect produced on said condensing portion by said cooling element.

7. A refrigerator comprising a cabinet having a food storage compartment, a primary refrigerating system including a cooling element located in one region of said compartment, a secondary refrigerating system comprising a cooling portion constructed and arranged for cooling another region of said compartment, and a condensing portion located in the vicinity of said cooling element, said condensing portion and said element being arranged for relative movement therebetween, and manually operable means for causing such movement to change the relative effect produced on said condensing portion by said cooling element.

8. A refrigerator comprising a cabinet having a food storage compartment, a primary refrigerating system including a cooling element located in one region of said compartment, a secondary refrigerating system comprising a cooling portion constructed and arranged for cooling another region of said compartment and a condensing portion located in the vicinity of said cooling element, said condensing portion and said cooling system being arranged for relative movement therebetween for regulating the heat transfer between said systems.
